ATTORNEYS

UNITED STATES PATENT OFFICE.

JAMES B. VINCENT, OF FLATBUSH, NEW YORK.

SASH-LOCK.

No. 821,842.

Specification of Letters Patent.

Patented May 29, 1906.

Application filed January 26, 1906. Serial No. 297,950.

To all whom it may concern:

Be it known that I, JAMES B. VINCENT, a citizen of the United States, residing at Flat-
5 bush, Long Island, in the county of Kings
and State of New York, have invented cer-
tain new and useful Improvements in Sash-
Locks, of which the following is a specifica-
tion, such as will enable those skilled in the
art to which it appertains to make and use
10 the same.

This invention relates to locks for win-
dows; and the object thereof is to provide
an improved device of this class which is sim-
15 ple in construction and operation and which
is invisible except from the inner side of the
window; and with this and other objects in
view the invention consists in a device of the
class specified constructed as hereinafter
20 described and claimed.

20 The invention is fully disclosed in the fol-
lowing specification, of which the accompa-
nying drawings form a part, in which the
separate parts of my improvement are desig-
nated by suitable reference characters in
25 each of the views, and in which—

Figure 1 is an inside view of the bottom
portion of the upper sash and the top portion
30 of the lower sash of a window and showing
said parts provided with my improved sash-
lock; Fig. 2, a section on the line 2 2 of Fig.
1, and Fig. 3 a plan view of the construction
as shown in Fig. 2.

In the drawings forming part of this speci-
fication I have shown at *a* the bottom part
35 of the upper sash of a window and at *b* the
top part of the lower sash, and the bottom
part of the upper sash is provided with a bot-
tom rail *a*² and the top part of the lower sash
40 with a top rail *b*², and in the practice of my
invention I form in the top part *b*² of the bot-
tom sash a longitudinal recess or chamber *b*³,
which opens backwardly through said part
45 of the upper sash at one end of said chamber,
as shown at *b*⁴, and the back surface of the
part *b*² of the bottom sash is also provided in
the form of construction shown with a coun-
tersunk plate *b*⁵, having an opening similar
50 to that of *b*⁴.

The bottom rail *a*² of the top sash *a* is pro-
55 vided in the front surface thereof with a
chamber or recess *a*³, adapted to register with
the opening *b*⁴, and secured to the front sur-
face of the part *a*² is a guard-plate *a*⁴, having
an opening which corresponds with the cham-
55 ber or recess *a*³.

Pivoted in the chamber or recess *b*³ in the
top rail *b*² of the bottom sash and ranging
longitudinally of said chamber is a dog *c*, said
dog being pivoted nearer one end of said
chamber than the other, as shown at *c*², and
60 the free end of said dog is provided with a
backwardly-directed nose *c*³, which is adapt-
ed to enter the chamber *a*³ when the sashes
are in their closed position, and formed in the
head of the dog *c* is a recess *c*⁴, and pivoted to
65 the front surface or face of the top rail *b*² of
the bottom sash *b* is a catch *d*, adapted to en-
ter the recess *c*⁴ and to hold the dog *c* out of
engagement with the top sash when the
sashes are not locked together. A guard-
70 plate *e* is also preferably secured to the top
rail *b*² of the bottom sash and provided with
an opening which corresponds with the cham-
ber *b*³ and to which the catch *d* is pivoted in
the form of construction shown, and said
75 plate is provided with stops *e*² and *e*³, which
are adapted to limit the movement of the
catch *d*, and in practice the dog *c* is pivoted
to the inner side of the said plate *e*.

The operation of this device will be readily
understood from the foregoing description,
when taken in connection with the accom-
panying drawings and the following state-
ment thereof. When the dog *c* is in the posi-
80 tion shown in full lines in Fig. 2, the sashes
are locked together, and when said dog is in
the position indicated in dotted lines in Fig.
2 and shown in full lines in Fig. 3 the sashes
85 are free to be moved or adjusted to any de-
sired position. The dog *c* may be held in the
unlocked position by the catch *d*, and when
this is done there is no danger of breaking the
90 dog or the nose thereof or of injuring the
sashes by the vertical movement of said
sashes when the dog is in the operative posi-
tion. The dog *c* is swung into the operative
95 position, as shown in Fig. 3, by pressing on
the head end thereof and into the inoper-
ative position, as shown in Fig. 3, by pressing
on the heel thereof.

Having fully described my invention, what
I claim as new, and desire to secure by Let-
ters Patent, is—

1. A sash-lock comprising an oblong cham-
ber formed in the front surface of the top rail
100 of a bottom sash, a dog pivoted in said cham-
ber and provided at one end with a nose
adapted to pass backwardly through said
rail and to enter a recess formed in the front
105 wall of the bottom rail of the top sash, and

means for holding the dog in both the operative and inoperative position, substantially as shown and described.

2. A sash-lock comprising an oblong chamber formed in the front surface of the top rail of a bottom sash, a dog pivoted in said chamber and provided at one end with a nose adapted to pass backwardly through said rail and to enter a recess formed in the front wall of the bottom rail of the top sash, and means for holding the dog in both the operative and inoperative position, comprising a catch pivoted to the top rail of the bottom

sash and a recess formed in the head of the dog and adapted to receive said catch when the dog is in its inoperative position, substantially as shown and described.

In testimony that I claim the foregoing as my invention I have signed my name, in presence of the subscribing witnesses, this 25th day of January, 1906.

JAMES B. VINCENT.
